UNITED STATES PATENT OFFICE.

PHILIP O. HOAG, OF NEWARK, NEW JERSEY, ASSIGNOR TO THE WHITEHEAD & HOAG COMPANY, OF NEWARK, NEW JERSEY, A CORPORATION OF NEW JERSEY.

NONREFILLABLE COIN BANK.

Application filed March 6, 1926. Serial No. 92,714.

This invention relates to a non-refillable bank adapted to be mounted on a card, hung upon a wall, carried in the pocket, or placed in any position where it is conveniently available for the reception and retention of 5 coins of similar or different denominations.

The main object is to provide a simple and comparatively inexpensive coin receptacle of this character for gratuitous distribution 10 among prospective contributors to various funds to be used for the reception of coin contributions to such funds, or may be used for the accumulation of individual or group savings to be opened by the individual or 15 other authorized person when and where desired.

One of the specific objects is to construct the device in such manner that the coin or 20 coins may be easily and quickly inserted into the bank and retained therein against removal without mutilating a certain part or parts of the device thereby preventing its reuse for the same purpose without reconstruction or replacements of the mutilated 25 part or parts.

Another specific object is to provide the outer case with an inner flexible lining of 30 celluloid or other material having a resilient portion thereof registering with a coin slot in the outer case so as to normally close the slot under its own tension and still permit displacement thereof by the insertion of a coin through the slot into the interior of the bank.

Other objects and uses relating to specific 35 parts of the device will be brought out in the following description.

In the drawings:

Figure 1 is a perspective view of one of 40 many different forms of coin holders which may be used embodying the various features of the invention.

Figure 2 is an enlarged sectional view of the same taken on line 2—2, Figure 1.

Figure 3 is a horizontal sectional view 45 taken in the plane of line 3—3, Figure 2.

Figures 4, 5, 6, 7 and 8 are perspective views of the cover-retaining ring, the closure disk, the main cover plate, the inner 50 resilient lining and the main receptacle respectively, as shown in Figure 1.

This device may be of any suitable size, shape, or material but in the specific form shown comprises a main cup-shaped receptacle 55 —1—, preferably of thin sheet metal

pressed, spun or otherwise molded to form a bottom portion —2— and an integral marginal rim —3— having an outturned flange —4— for receiving and retaining a cover presently described.

Any suitable part of the device, such as the rim —3—, may be provided with a slot or opening —5— of sufficient size to permit the individual coins to pass edgewise there-through although the size and shape of the opening and manner of inserting the coin may be varied without departing from the spirit of the invention.

Some portion of the cup and preferably the rim —3— is provided with spaced slits 70 —6— extending inwardly from the open end thereof to form a tongue —7— which is pressed inwardly a slight distance beyond the remaining portions of the rim to form an abutment for the opposite ends of an inner lining member —8—.

This lining —8— is preferably made of relatively thin celluloid or other light and resilient material divided at —9— and extended from the bottom —2— to the upper 80 edge of the receptacle —1— across the opening —5— with its ends abutting against opposite edges of the tongue —7— to hold it against lengthwise displacement.

The portions of the lining —8— adjacent 85 the ends of the slot —5— are provided with spaced transverse slits —10—, at one end connected by a lengthwise slit —11— to form a resilient closure —12— registering with said slot and extending from end to end thereof so as to be easily displaceable by the insertion of a coin through the slot into the interior of the receptacle and also to automatically close under its own resiliency after the coin has been deposited within the 90 receptacle.

The open end of the receptacle —1— is normally closed by a suitable cover having its marginal edge provided with a flange —13— and an inturned shoulder —14— in 100 interlocking engagement with the marginal flange —4— of the rim —3— for holding the cover in operative position.

This cover, as illustrated, comprises a main supporting plate —15—, a cover plate 105 —16— and a surface or finishing plate —17—, the supporting plate and cover plate —16— being preferably made of thin sheet metal or other suitable material while the surface or finishing plate —17— is usually 110

made of celluloid or paper with a celluloid coating capable of receiving informative or advertising matter.

The supporting plate —15— is preferably of greater area than the receptacle —1— and is provided with a down-turned marginal flange —18— around which the marginal edge of the surface or finishing plate may be crimped in the manner shown in Figure 1 to firmly hold those parts against relative displacement.

The supporting plate —15— is also provided with a central opening —19— of sufficient size to permit the coins to readily pass therethrough when the outer plates —16— and —17— are wholly or partially removed by proper mutilation of the surface or finishing plate —17— in a manner hereinafter described.

The cover plate —16— is of sufficient size to entirely cover the opening —19— but preferably is of less area than the supporting plate —15— so as to leave a marginal space between the outer edges of the plates —15— and —16— along which more or less of the surface of finishing plate —17— may be cut when it is desired to remove the cover plate —16— for discharging the coins from the receptacle.

The surface or finishing plate —17— is of greater diameter than both of the plates —15— and —16— so that its marginal edge may be returned inwardly and upwardly across the lower edge of the flange —18— for locking the inner and outer plates —15— and —17— to each other and also for holding the cover plate —16— in operative position across the opening —19—.

The inner lining —8— is inserted in the open end of the cup before the other parts are assembled, with its ends abutting against

the opposite ends of the tongue —7— thus bringing the closure —12— into registration with the slot —5—.

The cover including the parts —15—, 45 —16—, and —17— which have been previously assembled are placed over and upon the open end of the receptacle —1— and secured in operative position thereon.

After the parts have been assembled in the manner described the coins may be inserted one at a time through the slot —5— thereby deflecting the free end of the closure —12— inwardly sufficiently to allow the coin to pass thru the slit —11— and then into the interior 55 of the receptacle whereupon the closure —12— will return to its closed position under its own tension.

After the receptacle is wholly or partially filled and it is desired to remove the coins 60 the finishing plate —17— may be slit or cut by a knife or other implement in such manner as to allow the plate —16— to be withdrawn through the opening thus formed after which the receptacle may be inverted 65 to allow the coins to discharge through the opening —19— and thence through the opening in the finishing plate.

What I claim is:

In a non-refillable toy bank, a coin receptacle having a coin inlet, and a laminated portion composed of inner, outer and intermediate layers of sheet material, the inner layer having a coin outlet, the outer and intermediate layers being continuous across 75 the outlet, said intermediate layer being of less area than the outer layer and displaceable from across the outlet only by mutilation of the outer layer.

In witness whereof I have heretinto set my 80 hand this 23 day of February, 1926.

PHILIP O. HOAG.
